US0D1052347S

(12) United States Design Patent (10) Patent No.: US D1,052,347 S
(45) Date of Patent:  Nov. 26, 2024

(54) THREE PART PLATE

(71) Applicant: BabyBjörn AB, Sundbyberg (SE)
(72) Inventors: Johan Sandberg, Täby (SE); Anna Björk, Stockholm (SE)
(73) Assignee: BabyBjörn AB, Sundbyberg (SE)
() Term: 15 Years
(21) Appl. No.: 29/883,366
(22) Filed: Jan. 27, 2023

(30) Foreign Application Priority Data

Aug. 1, 2022 (EM) 009106529-0001
Aug. 1, 2022 (EM) 009106529-0002

(57) CLAIM

The ornamental design for a three part plate as shown and described.

DESCRIPTION

FIG. 1 is a top perspective view showing our new design for a three part plate,

FIG. 2 is a bottom perspective view thereof,

FIG. 3 is a top view thereof,

FIG. 4 is a bottom view thereof,

FIG. 5 is a front view thereof,

FIG. 6 is a rear view thereof; and,

FIG. 7 is a side view thereof, the opposite side being a mirror image thereof.
